CLAIM

The ornamental design for a vehicle seat, as shown and described.

DESCRIPTION

FIG. 1 is a perspective view of a vehicle seat showing our new design;

FIG. 2 is front elevational view thereof;

FIG. 3 is a right side elevational view thereof, the left side elevational view being a mirror image of the right side elevational view;

FIG. 4 is a rear elevational view thereof;

FIG. 5 is a perspective view of a second embodiment of a vehicle seat showing our new design;

FIG. 6 is a front elevational view thereof;

FIG. 7 is a right side elevational view thereof, the left side elevational view being a mirror image of the right side elevational view; and,

FIG. 8 is a rear elevational view thereof.
